[57] CLAIM

The ornamental design for a watch dial, as shown and described.

DESCRIPTION

FIG. 1 is a top plan view of a watch dial showing my new design; and,

FIG. 2 is a top plan view thereto, the broken-line showings of a wristwatch being environmental only and forms no part of the claimed design.

The dial is of no appreciable thickness and has a rear which is flat, plain and unornamented.

FIG. 2

FIG. 1
